UNITED STATES PATENT OFFICE.

PETER R. EKLUND, OF LITTLE SWAN, MINNESOTA.

RAILWAY-TIE.

1,325,081.

Specification of Letters Patent.

Patented Dec. 16, 1919.

Application filed March 24, 1919. Serial No. 284,622.

To all whom it may concern:

Be it known that I, PETER R. EKLUND, a citizen of the United States, residing at Little Swan, in the county of St. Louis and State of Minnesota, have invented certain new and useful Improvements in Railway-Ties, of which the following is a specification.

This invention relates to railway ties, and more especially to those which are metallic; and the object of the same is to produce a box-like tie whose body is filled with wire strands running in directions at right angles to each other so as to be compact and yet to an extent resilient.

A further object is to provide an improved form of rail fastening for ties of this character, which requires no access to the interior of the body.

Yet another object of the invention is to provide a movable connection between the top or cover and the body of the box.

These and other objects are carried out in a manner set forth below and shown in the drawings, wherein;

Fig. 1 is a side elevation of the tie complete,

Fig. 2 is an enlarged side elevation partly broken away and in section, of one end of the tie, and

Fig. 3 is a cross section on the line 3—3 of Fig. 1 also enlarged.

The body 1 of the tie is a box-like structure open at its top, and over the same lies a cover 2 provided along its sides and ends with flanges 3, the flanges at the sides being provided with upright slots 4 to receive rivets or bolts 5 which pass also through the sides of the body, and internally the cover is thickened or reinforced as at 6 at points where the rails R cross the same, while the cover is cut out in its upper face to provide channels or seats 7 for receiving the rails as best seen in Fig. 2.

The rail fastening consists of a plate 10 upturned at its inner end into a lip 11 overlying the base of the rail, the outer end of the plate having a depending stud 18 adapted to enter a socket 8 made in the top or cover 2 where the latter is reinforced. A screw 19 passes through the plate and takes into a threaded hole 9. Therefore the rail may be laid across the top of this tie without necessarily removing it from the body, and without reaching under or beneath said top or

into the body at all; and no spikes are needed, nor any nuts. Within the body is disposed a series of wires 12 extending transversely of the same, and wires 13 extending longitudinally of the same, all the wires being disposed in layers and every wire having a series of crimps in its body. It results that with the longitudinal wires for instance, a number of transverse wires pass over the first crimp, under the next crimp, and so on. This arrangement of wires is purposely adopted to give the body of the tie stability and weight, while not yet making it solid and unyielding as would be the case for instance, if the body were filled with cement. As a result, it is possible for the top or cover 2 to descend a little with respect to the body when an extremely heavy load passes over the tie, the provision of the rivets or bolts 5 and slots 4 being to permit such movement. The drawings are exaggerated for sake of clearness, but it is quite possible that the wire strand filler for the tie body could have a smaller or larger number of layers than shown thereon.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the appended claims.

Having thus fully described my invention, what I claim as new and desire to secure by Letters Patent, is:—

1. The herein described railway tie made up of a box-like body filled with strands of wire running in different directions at right angles to each other, and a cover for the body resting on the strands.

2. The herein described railway tie made up of a box-like body filled with strands of wire running in different directions at angles to each other, and a cover for the body having a surrounding flange inclosing said body, the cover being reinforced on its under side and resting on said wires.

3. The herein described railway tie made up of a box-like body filled with strands of wire running in different directions at right angles to each other, a cover for said body having a surrounding depending flange provided with upright slots, bolts in the side

walls of the body and projecting through said slots, and means for attaching the rails to the cover.

4. A filler for hollow railway ties made up of a series of strands of wire running in directions at angles to each other and crimped throughout their length.

5. A filler for hollow railway ties made up of a plurality of series of wire strands, 10 those in one series running in a direction at right angles to those in the series adjacent.

6. A filler for hollow railway ties made up of a plurality of series of wire strands, 15 those in one series running in a direction at right angles to those in the series adjacent, and all wires being crimped throughout their length.

7. A filler for hollow metallic railway ties consisting of a series of longitudinal wires 20 crimped throughout their length, a superposed series of transverse wires underlying one crimp and overlying the next and so on, and repetitions of these series.

8. The herein described railway tie made

up of a box-like body filled with strands of 25 wire running horizontally and resting upon each other, and a cover for the body resting on the strands.

9. The herein described railway tie made up of a box-like body filled with strands of 30 wire running in different directions and in horizontal planes and resting upon each other and a cover for the body resting on the strands.

10. The herein described railway tie made up of a box-like body filled with strands of 35 wire, and a cover for the body resting on the strands.

11. The herein described railway tie made up of a box-like body filled with strands of 40 wire running in different directions, and a cover for the body resting on the strands.

In testimony whereof I affix my signature in presence of two witnesses.

PETER R. EKLUND.
